(57) **CLAIM**

We claim the ornamental design for a battery package, as shown and described.

DESCRIPTION

FIG. 1 is a perspective view of a battery package showing our new design;

FIG. 2 is a front view shown on a reduced scale relative to FIG. 1;

FIG. 3 is a rear view thereof;

FIG. 4 is a left side view shown on an enlarged scale relative to the preceding figures;

FIG. 5 is a right side view thereof;

FIG. 6 is a top view shown on a further enlarged scale; and, FIG. 7 is a bottom view thereof.

The broken lines are included for the purpose of illustrating portions of the battery package that form no part of the claimed design.
